(57) **CLAIM**

We claim the ornamental design for aerosol dispenser for a pressurized container, as shown and described.

DESCRIPTION

FIG. 1 is a left, top, front perspective view of an aerosol dispenser for a pressurized container embodying our new design;

FIG. 2 is a right, top, rear perspective view of the aerosol dispenser;

FIG. 3 is a top plan view of the aerosol dispenser;

FIG. 4 is a front elevational view of the aerosol dispenser;

FIG. 5 is a left side elevational view of the aerosol dispenser;

FIG. 6 is a right side elevational view of the aerosol dispenser; and,

FIG. 7 is a rear elevational view of the aerosol dispenser.

The bottom of the aerosol dispenser forms no part of the claimed design.

The broken lines in the drawings are for illustrative purposes only and form no part of the claimed design.
